COMBINATION INTAKE MANIFOLD AND TAPPET COVER GASKET

Robert S. Rarey, Birmingham, Mich., assignor to Chrysler Corporation, Highland Park, Mich., a corporation of Delaware

Filed Aug. 18, 1958. Ser. No. 755,477

10 Claims. (Cl. 123—55)

This invention relates to V-type internal combustion engines utilizing unitary structures of intake manifold gaskets and tappet chamber covers, and further relates to the mounting surface structure of said engines for accommodating these unitary structures, the broad features of which are disclosed in my copending joint application with Frederick R. Shrimpton Serial No. 749,703, filed July 21, 1958, now Patent No. 2,941,521, and owned by applicants' assignee.

Heretofore, intake manifold gaskets and tappet chamber covers and the gaskets therefor, for use on V-engines were individually produced and individually assembled on the engine. Such individual production and assembly inherently results in increased machinery and labor costs which is to be avoided in competitive industry. The separate structure on the engine required for the mounting of manifold gaskets and tappet chamber covers and gaskets did not heretofore utilize the intake manifold mounting surfaces of the heads which, it has been discovered, provides a convenient and adequate surface for the attachment of the tappet chamber cover to the engine and eliminates the need for side flanges on the engine for mounting said cover. Furthermore, it has been discovered that by casting or machining, the upper portions of the end walls of the engine block and the intake manifold mounting surfaces of the heads into a substantially continuous mounting wall the aforementioned combined structure could be readily made to fit on said continuous wall and be clamped thereto to simultaneously provide intake manifold gaskets and a tappet chamber cover for said engine.

An object of this invention is to provide an integral structure capable of being produced by a single stamping operation and which can adequately serve as intake manifold gaskets and a tappet chamber cover for a V-engine.

Another object is to eliminate the need for separate intake manifold gaskets and tappet chamber covers and the gaskets for said covers.

Another object is to combine engine block and engine head structure to provide a substantially continuous mounting wall for the unitary structure of intake manifold gaskets and a tappet chamber cover.

Further objects and advantages will become apparent with reference to the following drawings and description, in which:

FIGURE 1 represents a top elevational view of the unitary structure of intake manifold gaskets and tappet chamber cover;

FIGURE 2 represents an end view of the unitary structure of FIGURE 1;

FIGURE 3 is a view taken along line 3—3 of FIGURE 1 in the direction of the arrows;

FIGURE 4 is a view taken along line 4—4 of FIGURE 1 in the direction of the arrows;

FIGURE 5 represents a top elevational view of a V-engine with the intake manifold and a portion of the unitary structure of intake manifold gaskets and tappet chamber cover removed;

FIGURE 6 represents a transverse cross sectional view of a V-engine showing the intake manifold and combined structure of intake manifold gaskets and tappet chamber cover in place;

FIGURE 7 represents a sectional longitudinal view of the V-engine of FIGURE 6 with the intake manifold re-

2

moved taken along line 7—7 of FIGURE 6 in the direction of the arrows; and

FIGURE 8 is an end view of the assembled V-engine with the intake manifold and the unitary structure of intake manifold gasket and tappet chamber cover in position.

Referring to the drawings and in particular to FIGURES 1—4, unitary structure 10 represents intake manifold gaskets 12 integral with the opposite upturned sides

13 of a trough shaped tappet chamber cover 14. Gaskets 12 form, in effect, side flanges or manifold flanges on said opposite sides 13 and extend therefrom in approximately the plane of said sides. Pairs of intake apertures 16 are located in each gasket 12 on either side of an exhaust crossover aperture 18 therein. Apertures 16 are spaced so as to coincide with the conduits 20 of intake manifold 24, and apertures 18 are located to coincide with hot spot crossover conduits 22 of intake manifold 24 (see FIGURE 6). Apertures 16 and 18 also correspond in position to conduits 21 and 23 respectively in heads 26 of a V-engine 28. An air coolant chamber 27 for exhaust passage 23 which connects to hot spot crossover conduit 22 partially surrounds conduit 23 in each of said heads 26. Encircling each of the apertures 16 and 18 and manifold clamping bolt apertures 32 in intake manifold gaskets 12 is a bead 30 raised from the upper surface of structure 10 and extending continuously around the entire periphery of said structure adjacent the outer edge thereof.

30 End flanges 34 integral with the opposite upturned ends 35 of cover 14 and extending at an angle therefrom are provided with clamping bolt apertures 36. Clamping bars 40 having clamping bolt apertures 41 therein corresponding in position to apertures 36 in end flanges 34 are adapted to be mounted on said end flanges as shown in FIGURE 5. Support walls 38 integral with block 33 of V-engine 28 and spanning the cylinder banks 50 and 52 of said engine are provided with threaded clamping bolt receiving apertures 31 which correspond in position to the clamping bolt apertures of end flanges 34 and clamping bars 40. In the assembled condition shown in FIGURES 5 and 8, clamping bars 40 are mounted on end flanges 34 which flanges are mounted on walls 38. This assembly is secured to support walls 38 by bolts 42 which bolts pass through the aligned apertures 41 and 36 and are threadably secured in apertures 31 in walls 38.

As shown in the broken away portion of the gasket of FIGURE 5, the upper portions of the end walls of engine 28 forming support walls 38 and the intake manifold mounting walls 39 of heads 26 form a continuous mounting surface upon which the unitary structure 10 is mounted. Support walls 38 and intake manifold mounting walls 39 also define the perimeter of the opening through the block leading into the tappet chamber 37 as shown in FIGURE 5. Bead 30 which projects up from the structure 10 is designed to create an oil tight seal by becoming crushed under the intake manifold 24 and bars 40 as said manifold and bars are clamped by bolts to said mounting walls 39 and supports 38 respectively.

60 Stiffening ribs 44 and 46 are formed in trough 14 of the cover by pressing grooves in said trough. These ribs prevent the cover from vibrating too violently during engine operation which vibration might cause a defect in the seal formed by bead 30. It is noted that trough 14 is designed so as to accommodate the lowest portion of the intake manifold, and the above mentioned stiffening ribs also prevent said trough from vibrating against said manifold portion.

I claim:

70 1. A combination structure of intake manifold gaskets and a valve tappet chamber cover comprising a trough like body having narrow flanges at the opposite longitudi-

5
nal ends thereof and having side flanges extending longitudinally thereof, said side flanges each having a plurality of intake apertures and a single exhaust crossover aperture therein, a single bead extending continuously around said combination structure adjacent the periphery thereof and a plurality of ribs in said body providing stiffness thereto.

2. A unitary structure of intake manifold gaskets and a valve tappet chamber cover comprising a trough like body having ribs extending longitudinally thereof and a plurality of transverse ribs intersecting said longitudinal ribs, a flange on each end of said trough having spaced apertures therethrough for receiving clamping bolts, a manifold flange on each side of said trough and integral therewith, each said manifold flange having two pairs of side by side intake apertures spaced therealong, a single exhaust crossover aperture in each said manifold flange intermediate said pairs of intake apertures, a plurality of clamping bolt apertures spaced along each said manifold flange, and a continuous sealing rib adjacent the periphery of said structure and the peripheries of the apertures therethrough.

3. A unitary structure providing intake manifold gaskets and a valve tappet chamber cover comprising a trough like body having a manifold flange on each longitudinal edge thereof, each said manifold flange having therein two pairs of side by side intake apertures and a single crossover aperture located between said pairs of intake apertures, a single bead extending around said structure and around each aperture therein adjacent the peripheries thereof, a longitudinal rib in the bottom of said body and a plurality of transverse ribs in said body intersecting said longitudinal rib and providing stiffness to said body.

4. In a V-engine having a cylinder block with opposed cylinder banks and heads and an intake manifold positioned on said heads intermediate and spanning said banks, a unitary structure comprising a trough like body having opposite end flanges seating on said block and having side flanges seating on said heads, said end and side flanges being coextensive to surround said trough like body, a plurality of stiffening ribs running longitudinally and transversely of said body, a plurality of apertures in said side flanges for coinciding with apertures in said heads, and a continuous bead-like projection on the upper face of said flanges extending around the periphery of said coextensive flanges and around the peripheries of each of said apertures in said side flanges.

5. In a V-engine having a block with opposed cylinder banks and heads extending therefrom an intake manifold positioned on said heads intermediate said banks, an integral structure comprising a trough like body, said body having opposite end flanges extending outwardly from said body in a plane substantially parallel to the bottom of said body and seating on said block, opposite side flanges integral with said body and diverging from each other at a substantially right angle and seating on said heads, said flanges being coextensive to surround said trough like body, a plurality of stiffening ribs running longitudinally and transversely of said body, a plurality of apertures in said side flanges for coinciding with apertures in said heads, and a continuous bead-like projection on the upper face of said flanges extending around the periphery of said structure and around the peripheries of said apertures in said side flanges.

6. In a V-engine, a block having opposed cylinder banks and having heads on said block and extending therefrom, an intake manifold lying intermediate said banks and said heads and having conduits positioned on said heads, each of said heads having conduits therein corresponding in position to said manifold conduits, each of said heads having an intake manifold mounting wall thereon, said block having a support wall at each end thereof connecting said cylinder banks, said support walls and said intake manifold mounting walls forming a sub-

stantially continuous supporting wall, and a unitary structure of intake manifold gaskets and a tappet chamber cover mounted on said continuous supporting wall to provide a seal between said intake manifold and said heads.

7. In a V-engine, a block having opposed cylinder banks and having heads on said block and extending therefrom, a tappet chamber intermediate said banks, an intake manifold having conduits therein corresponding in position to said manifold conduits, each of said heads having an intake manifold mounting wall thereon, said block having a support wall at each end thereof connecting said cylinder banks, said support walls and said intake manifold mounting walls forming a substantially continuous supporting wall, and a unitary structure of intake manifold gaskets and a tappet chamber cover mounted on said continuous supporting wall, said manifold gaskets of said structure having apertures therein corresponding in position to the conduits of said intake manifold being mounted on said intake manifold gaskets and secured to said intake manifold mounting walls.

8. In a V-engine, a block having a tappet chamber therein, an opening in the top of said block communicating with said tappet chamber, opposed cylinder banks and heads extending angularly from said block, an intake manifold positioned intermediate said banks, said manifold having intake conduits spaced therein, each of said heads having conduits therein corresponding in spaced position to said intake manifold conduits, each of said heads having an intake manifold mounting wall thereon, a support wall at each end of said block connecting said cylinder banks, said intake manifold mounting walls on said heads and said support walls on said block forming a continuous mounting wall defining said opening in said block, a unitary structure of intake manifold gaskets and a tappet chamber cover mounted on said continuous mounting wall, said manifold gaskets having apertures therein corresponding in position to the conduits of said intake manifold and said heads, and a continuous sealing bead raised up from the upper surface of said combined structure and extending peripherally around said unitary structure and the apertures therein and spaced from the edges of said unitary structure and said apertures, said manifold being mounted on said gaskets and secured to said heads.

9. In a V-engine, a block having a tappet chamber therein, an opening in the top of said block communicating with said tappet chamber, opposed cylinder banks and heads extending angularly from said block, an intake manifold positioned intermediate said banks, said manifold having intake conduits spaced therein, each of said heads having conduits therein corresponding in spaced position to said intake manifold conduits, each of said heads having an intake manifold mounting wall thereon, a support wall at each end of said block connecting said cylinder banks, said intake manifold mounting walls on said heads and said support walls on said block forming a continuous mounting wall defining said opening in said block, a unitary structure of intake manifold gaskets and a tappet chamber cover mounted on said continuous mounting wall, said cover having end flanges resting on said support walls of said block, said manifold gaskets having apertures therein corresponding in position to the conduits of said intake manifold and said heads, a continuous sealing bead raised up from the upper surface of said combined structure and extending peripherally around said unitary structure and the apertures therein and spaced from the edges of said unitary structure and said apertures, said manifold being mounted on said gaskets and secured to said heads, and a clamping bar mounted on each said end flange of said cover and secured to said support walls on said block.

10. A sheet like member having a trough therein, end

portions integral with said trough and curving upwardly and outwardly from the bottom thereof to define narrow end flanges extending substantially parallel to the bottom of said trough, side portions integral with said trough and curving upwardly from the bottom thereof forming side flanges, said end flanges lying below said side flanges, a plurality of stiffening ribs in the bottom of said trough, a plurality of apertures in each said side flange, the ends of said side flanges being directly connected to the ends of said end flanges to form a continuous flange, and a continuous sealing bead projecting upwardly from the surface of said sheet like member adjacent the periphery

thereof and encircling said member and each of said apertures in each said side flange.
